US0D1049099S

(12) **United States Design Patent** (10) Patent No.: **US D1,049,099 S**
(45) Date of Patent: ** Oct. 29, 2024

(54) **ELECTRONIC DEVICE**

(71) Applicant: **Apple Inc.**, Cupertino, CA (US)

(72) Inventors: **Jody Akana**, Los Altos Hills, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Abidur Rahman Chowdhury**, San Francisco, CA (US); **Clara Geneviève Marine Courtaigne**, Palo Alto, CA (US); **Markus Diebel**, San Francisco, CA (US); **Jonathan Gomez Garcia**, San Francisco, CA (US); **M. Evans Hankey**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Joe Sung-Ho Tan**, Vienna (AT); **Clement Tissandier**, San Francisco, CA (US); **Eugene Antony Whang**, San Francisco, CA (US)

(73) Assignee: **Apple Inc.**, Cupertino, CA (US)

(**) Term: **15 Years**

(21) Appl. No.: **29/888,015**

(22) Filed: **Mar. 27, 2023**

Related U.S. Application Data

(63) Continuation of application No. 29/778,036, filed on Apr. 9, 2021, now Pat. No. Des. 982,006.
